G. A. WHEELER.
ELEVATOR.

(Application filed June 15, 1897. Renewed Oct. 31, 1898.)

(No Model.)

INVENTOR.

G. A. Wheeler,
BY G. W. G. Vassar

ATTORNEY.

UNITED STATES PATENT OFFICE.

GEORGE A. WHEELER, OF NEW YORK, N. Y., ASSIGNOR OF ONE-HALF TO
CHARLES D. SEEBERGER, OF CHICAGO, ILLINOIS.

ELEVATOR.

SPECIFICATION forming part of Letters Patent No. 617,789, dated January 17, 1899.

Original application filed April 16, 1897, Serial No. 632,428. Divided and this application filed June 15, 1897. Renewed October 31, 1898, Serial No. 695,053. (No model.)

To all whom it may concern:

Be it known that I, GEORGE A. WHEELER, a citizen of the United States, and a resident of New York, in the county of New York and State of New York, have invented certain new and useful Improvements in Elevators, of which the following is a specification:

This application is a division of my application filed April 16, 1897, Serial No. 632,428.

10 My invention is an improvement in that class of elevators which are used by a continuous procession of foot-passengers, as in the case of the approach to a bridge or elevated viaduct.

15 The object of my improvement is to increase the safety and efficiency and to decrease the power necessary to operate such a structure.

20 The elevator shown and described in United States Letters Patent No. 479,864, dated August 2, 1892, issued upon my application, forms the basis for the improvements herein-after described.

25 I provide a frame or track support of any suitable description and a traveling structure composed of a series of moving steps, preferably pivoted together through the medium of endless chains or belts, and I may so arrange the course, way, or track in which the steps 30 move that each step describes a gradual curve as it passes from its landing point or level to its inclined path, or vice versa. The track is fixed in a horizontal position for one part or section and in an inclined position for one 35 part or section. The junction between the two sections may be a curve to which said sections are tangent. By this means I avoid friction and am enabled to maintain the chain or jointed structure at the proper tension. I 40 am also able by this means to avoid abrupt changes in the direction of movement of the steps. Each step is composed of a horizontal portion, or tread and a vertical portion, or rise. The exterior surface of the riser is 45 convex, and the arc of its convexity is approximately the same as the arc described relative thereto by the adjacent steps while passing from an inclined to a horizontal portion of the track, or vice versa. By this con-

struction when the steps are arranged to move 50 from a position where the line of travel is horizontal to that where it is at an incline, or vice versa, no material space or separation will occur between adjacent steps. The described are is preferably the arc struck by a 55 radius equal to the length of chain connecting two successive adjacent steps, if a chain is employed, and I prefer to so arrange the arc of convexity that the point of a succeeding step in passing from the incline to the horizontal 60 shall gradually and slightly diverge.

The accompanying drawings illustrate my invention applied to one form of an elevator.

Figure 1 is a longitudinal sectional view of the structure consisting of a track and a 65 series of connected steps. Fig. 2 is a detail sectional view of one of the moving steps, showing the convex form of the riser and the arc described by the succeeding step in passing from a position where the line of travel 70 is horizontal to that where it is at an incline, or vice versa—that is, when the steps in use are changing from a position where the treads are in parallel planes to one where they are in the same plane.

75 I provide two parallel fixed angle-iron channels constituting the frame of the elevator. These channels are located in parallel planes, and I prefer to construct them of sections riveted together.

80 R and R' indicate the rails fixed to the described channel-iron, upon which rails the wheels m and n travel. The rails are horizontal for a portion of their course or extension and at an incline for a portion of their 85 course or extension, the junction between the described horizontal and inclined portions being a curve with respect to which the described horizontal and inclined portions are tangent.

90 Each of the movable steps is composed of a series of parallel brackets, like l, preferably of stamped sheet metal, as steel, having hubs 19. The series of brackets constituting a step are arranged upon axles h, bearing 95 wheels or rollers, like m and n. The riser of each step upon its outer surface s is convex, the arc of convexity being substantially

the same as the arc described by the advance point *e* of a succeeding step relative to the preceding step as it swings or turns at a point in its course in passing from a position where the line of travel is horizontal to that where it is at an incline, or vice versa. The described arc is preferably one struck on a radial line in length equal to the length of a link or chain connecting two successive adjacent steps, and I prefer to so locate the center of the arc or otherwise change the curvature of the arc that as the rear step comes to the same level as the preceding step in passing from an inclined to a horizontal portion of the track its nose will gradually recede from the surface of the riser, as shown in Fig. 2. The object of employing this construction is to have the following step continuously swinging away from the riser of the preceding step, so that if at any point a passenger's foot comes in contact with the riser the next instant the foot is carried away, thus preventing any scraping of the foot against the riser.

25 At each terminal there is a stationary landing, *L* indicating the lower landing, and *U* the upper landing, so that a passenger riding on a step may easily transfer from one to the other, as from the moving step to the stationary landing, or vice versa.

W *W* represent power-driven wheels. I prefer to apply the power at or near the upper landing.

It is a moving hand-rail, and *C* is a chain 35 through the medium of which the wheel *W* is driven to propel the moving hand-rail.

It is to be understood that the series of steps shown are preferably united by pivoted links into a continuous chain-like structure 40 and that the power-driven movement thereof is from left to right, as shown in the drawings, although my curved risers might be applied to similar steps not connected by links, but held to move together by confining-ways 45 or some such structure.

I may, if desired, provide idler-sprockets *J* to produce proper tension in the chain and to guide and control the moving structure.

What I claim, and desire to secure by Letters of Patent, is—

1. In an elevator of the character described, a series of steps each consisting of a tread and a riser, each riser having an exterior convex surface, said steps being united at each end by links into an endless chain, wheels upon which said chain is supported, and a track for said wheels arranged in horizontal sections joined to inclined sections, substantially as described.
2. The combination in an elevator of the character described of horizontal and inclined

track-sections, a series of steps each composed of a tread and a riser, the latter having an exterior convex surface, pivoted links between successive steps uniting them into an endless chain and a series of antifriction devices supporting the chain structure upon the track, substantially as described.

3. In an elevator of the character described, a track arranged in horizontal and inclined sections, said sections being united, a series of steps a series of links flexibly uniting said series of steps into an endless movable structure, each step being composed of a tread and a riser, said riser having a convex exterior surface, the arc of curvature being substantially equal to an arc having a radius in length equal to the link connecting adjacent steps, substantially as and for the purpose described.

4. In an elevating apparatus, a series of traveling steps arranged to move together, the treads of which are adapted to remain severally horizontal whether the steps be moving horizontally or on an incline, the said steps being provided with risers, having convex surfaces toward the adjacent edge of adjacent steps substantially as and for the purpose described.

5. In an elevating apparatus, a series of traveling steps arranged to move together, the treads of which are adapted to remain severally horizontal whether the steps be moving horizontally or on an incline, the said steps being provided with curved risers having convex surfaces toward the adjacent edge of adjacent steps adapted to prevent any divergence between the riser and the edge of the adjacent step in passing from an inclined to a horizontal portion of the track, and vice versa.

6. The combination in an elevator, of a series of carriages constructed to move from inclined to horizontal positions, and vice versa, each carriage having a tread and a riser curved outward to substantially coincide with the path traveled, relative to said carriage, by the edge of the adjacent tread in moving from one position to another, the curve of the riser being so laid out that the edge of the following tread diverges slightly from the riser in passing from an inclined to a horizontal position, substantially as and for the purposes described.

Signed at New York, in the county of New York and State of New York, this 14th day of June, A. D. 1897.

GEORGE A. WHEELER.
